THOMAS WALLWORTH, OF NEWTON HEATH, GREAT BRITAIN.

Letters Patent No. 74,641, dated February 18, 1868; antedated February 14, 1868.

IMPROVEMENT IN COMPUTING-APPARATUS.

The Schedule referred to in these Letters Patent and making part of the same.

TO ALL WHOM IT MAY CONCERN:

Be it known that I, T. WALLWORTH, of Newton Heath, Lancaster county, Kingdom of Great Britain and Ireland, have invented certain Improvements in Machinery or Apparatus for Computing or Reckoning Quantities and Amounts; and I do hereby declare the following to be a full, clear, and exact description of the same, reference being had to the accompanying drawing, and to the letters of reference marked thereon.

The invention is designed for the purpose of indicating and showing the products arising from the multiplication of any two sets of numerals together for which the tables and instrument may be arranged.

The apparatus consists of a disk, enclosed between two outer plates, and mounted on a central shaft or axis, at each end of which a finger or pointer and a handle are secured, by which the fingers are turned to point to any multiplying-numerals, and which also turns the internal disk. In the outer plate are two slots, made from the periphery towards the centre, down one side of each of which slots are marked the "multiplicands" or numbers to be multiplied, and round the outer edge of each of these plates the "multipliers" are arranged. On both faces of the internal disk columns of numerals are marked, which have been previously calculated and ascertained, and which represent the product of multiplication between the numerals on the edge of the plates or "multipliers," and the numerals down the slots or multiplicand; thus, when one of the pointers is turned to any "multiplier" on the edge of the plate, the disk is also turned, and the product appears through the slot opposite to the multiplicand on the side of the slot.

This combination and arrangement of apparatus may be mounted on a vertical spindle, so as to turn round to read both sides, and a series of the dials and plates may be arranged behind each other, and adapted and calculated for weights, measures, money, interest, or other tables, and where a series are employed, each apparatus may be made to fall into a horizontal position to clear the others, so that both sides may be legible by supporting the spindles on pivots, and making a slot in the framing.

In order that the invention may be better understood and explained in detail, I have hereunto attached a sheet of drawings, having letters of reference marked thereupon.

Figure 1 represents a front elevation of the apparatus for ascertaining and indicating the product or amount arising from the multiplication of any two sets of numerals together. This view also shows the arrangement and position of the aperture in the outer plate or cover through which one line or series of numerals appears, which are marked and arranged on the internal wheel or disk, and which represent the products of the numerals on the edge of the aperture, and on the outer plate, multiplied by each other.

Figure 2 represents the internal disk detached, the arrangement of the numerals being partly shown in radial lines.

Figure 3 represents a vertical section of the apparatus.

Figure 4 represents the front elevation of a similar apparatus, arranged in sets of four or more, in order that amounts or products in money, interest, weight, or measure, may be ascertained and indicated, each disk being only calculated and arranged in accordance, and the amount may be ascertained from any particular disk by causing such disk to assume the horizontal position shown.

Figure 5 represents a side elevation of a number of disks arranged for the aforesaid purpose.

In figs. 1, 2, 3, 4, and 5, *a* is the stand or support of the plates and disks, in which such plates and disks may be arranged to indicate on both sides, and turned upon the shaft or axis *a'*, as seen in fig. 1, or any one of the numbers, as seen in figs. 4 and 5, may be withdrawn from the stand and caused to assume a horizontal position. In the outer plates *b b*, which enclose the internal disk, slots or openings *c c* are formed, which extend from the periphery towards the centre. Down one side, *d*, of each of these slots, are marked the "multiplicand" numbers to be multiplied, and round the outer edge of each of these plates the "multipliers" are arranged. On both faces of the internal disk, columns of numerals which have been previously calculated, are marked, which represent the product of multiplication between the numerals on the edge of the plates or multipliers and the numerals down the sides of the apertures or multiplicands. Thus, when the pointer *e* is turned to any multiplier on the edge of the plate, the internal disk is also turned, being mounted on the same shaft, *f*, and the numerals which appear through the opening opposite to or in line with each multiplicand represent the product of the multiplication of one of the other. For instance, if an article is six and one-half pence a pound,

(which rate is indicated on the scale d), the cost of two pounds will be found by turning the pointer e to the figure 2, when the figures $\frac{1}{2}$ (indicating one shilling one penny) will appear through the opening c , opposite the number $6\frac{1}{2}$ on the scale d . In like manner, by turning the pointer to the figure 6, the cost of six pounds ($\frac{3}{2}$, three shilling three pence) will be brought opposite the number $6\frac{1}{2}$. When the fractions in the multiplicand are stated in quarters instead of halves, the disk is turned so as to expose the graduations on the opposite side. It will be apparent that when a different system of currency is employed the graduations must be altered.

I claim as my invention, and desire to secure by Letters Patent—

A plate, b , with an opening, c , and with graduations at its edges and at the edges of the opening, in combination with a graduated revolving disk, having figures arranged in radial rows, and with a pointer secured to and turning with the disk, the whole being constructed, arranged, and operating substantially as described.

In testimony whereof, I have hereunto signed my name to this specification in the presence of two subscribing witnesses.

Witnesses:

JOHN L. DAVIES,
JNO. HUGHES.

T. WALLWORTH.
